CLAIM

The ornamental design for a vital signs detector, as shown and described.

DESCRIPTION

FIG. 1 is a front view of a vital signs detector showing our new design;

FIG. 2 is a back view thereof;

FIG. 3 is a left view thereof;

FIG. 4 is a right side view thereof;

FIG. 5 is a top view thereof;

FIG. 6 is a bottom view thereof;

FIG. 7 is a perspective view thereof;

FIG. 8 is a perspective view thereof in an alternate configuration with a portion thereof extended; and,

FIG. 9 is another perspective view thereof.

The broken line illustrate portions of the vital signs detector that form no part of the claimed design.
